UNITED STATES PATENT OFFICE.

AARON HILL, OF LOS ANGELES, CALIFORNIA, ASSIGNOR OF ONE-FOURTH TO RAYMOND IVES BLAKESLEE, OF ALHAMBRA, CALIFORNIA.

GANG-DRILL.

1,133,243.

Specification of Letters Patent. Patented Mar. 23, 1915.

Application filed January 21, 1914. Serial No. 813,433.

To all whom it may concern:

Be it known that I, AARON HILL, a citizen of the United States, residing at Los Angeles, in the county of Los Angeles and State of California, have invented new and useful Improvements in Gang-Drills, of which the following is a specification.

This invention relates to gang drills or machines with a plurality of drills for simultaneous or related operation; and it has for its object to provide improved gang drill mechanism which will be superior in point of relative simplicity and inexpensiveness taken in connection with positiveness in operation, facility in control, speed of operation, and facility in applying and handling the work upon which the drills operate.

With the above and other objects in view, the invention consists in the novel and useful provision, construction, combination and relative arrangement and association of parts, members and features, all as hereininafter described, shown in the drawings and finally pointed out in claims.

In the drawings: Figure 1 is a front elevation of a gang drill mechanism constructed and organized in accordance with the invention; Fig. 2 is a side elevation of the same; Fig. 3 is a transverse sectional view on the line 3—3 of Fig. 4, looking in the direction of the arrows; Fig. 4 is a similar view taken upon the line x^4 — x^4 , Fig. 1, and looking in the direction of the appended arrow; Fig. 5 is a detail vertical transverse sectional view taken upon the line x^5 — x^6 , Fig. 1, looking in the direction of the appended arrow; and Fig. 6 is a detail transverse sectional view taken on the line x^6 — x^6 , Fig. 1, and looking in the direction of the appended arrow; Fig. 7 is a detail horizontal transverse sectional view taken on the line x^7 — x^7 , Fig. 2, and looking in the direction of the appended arrows; and, Fig. 8 is a fragmentary elevation showing closely grouped relation between several of the spindles and sprockets and attendant features shown in Fig. 1. Figs. 3 to 6 inclusive are upon an enlarged scale.

Corresponding parts in all the figures are designated by the same reference characters.

Referring with particularity to the drawings, A, A designate each a separate drill element all being shown as applied to work

55 B such as a structural iron beam which is

to receive a plurality of spaced holes, the drills being shown as vertically arranged, and the work being mounted upon a movable support C slideable vertically at its ends by keepers 7 upon end frame uprights 8, 60 which also support a horizontal top frame member 9 carrying drill spindle bearings 10, one for each drill, each spindle 11 being provided with a sprocket 12, the said sprockets throughout the series of spindles 65 being in staggered relation so that an upper tier of sprockets is provided for engagement by a link belt 13 passing about a drive sprocket 14 at one end of the frame member 9 and about an idler 15 at the other end of 70 the frame member 9; the lower tier of sprockets 12 being engaged with a link belt 16 operating around a drive sprocket 17 beneath the idler sprocket 15, and an idler sprocket 18 beneath the drive sprocket 14. 75 The idler sprocket 18 is loose upon a vertical drive shaft 19 suitably journaled in the end of the frame member 9, the drive sprocket 14 being keyed to said shaft 19. The idler 15 is loose upon a drive shaft 20 80 to which is keyed the drive sprocket 17. Said drive shafts are adapted to be rotated by operating means D, jointly or separately, such means including main line shafts 21 and 22 at the opposite ends of the 85 machine, and journaled in brackets 23 and 24 upon the frame member 9, such shafts having gears 25 and 26 meshing respectively with other gears 27 and 28 at the upper ends of the drive shafts 20 and 19. The 90 shafts 21 and 22 are provided with loose pulleys 29 and 30 respectively with which coöperate friction clutches 31 and 32 splined or feathered to the shafts 21 and 22, such clutches being cross-connected by a link rod 95 33 joining the arms 34 and 35 of the clutches.

E designates operating means for the vertically movable work support C, the same including a drive shaft 36 journaled in the end supports 8 and carrying cams 37 disposed in positions to play upon rollers 38 mounted at the forward ends of pivotally operating elevated arms 39 which are adjustably connected with and beneath the 105 work support C, as at 40, so that the path of vertical play of the work support may be predetermined; so as to accommodate variations in drill length and in work dimensions and depth of drilling. One arm 110

39, extends rearwardly of its pivotal center 41, as at 42, and a rigid link rod 43 extends between such extension and the shorter end of a bell crank 44, the upper end 5 of which is adjustably connected with the link rod 33, as at 45. Power applying belts 46 rotate the loose pulleys 29 and 30. The operating means E also include a worm 47 at the lower end of the drive shaft 19, a 10 worm gear 48 meshing with the same and upon a short shaft 49 carrying a sprocket 50 which through a link belt 51 rotates the operating shaft 36 which carries loosely a sprocket wheel 52, the hub 52^a of which is 15 provided with a plurality of pivoted dogs or pawls 53 adapted to co-act with teeth 54 upon the inner surface of an annulus 55 keyed, as at 56, to the shaft 36. Each pawl is pressed toward engaging position by a 20 compression spring 52^b between the same and the hub of the sprocket wheel. Hand spokes 57 radiate from the annulus 55, and by means of the same the shaft 36 may be given movement independently of the dogs 25 and the sprocket wheel to position the work support as desired through the aid of the cams 37 prior to the setting up operation of the machine. When the rollers ride over the noses of the cams and the work support 30 is thus permitted to drop the link 43 and bell crank 44 move the link rod 33 to disconnect the clutches 31 and 32 from the pulleys 29 and 30, terminating rotation of the drive shafts 20 and 19 and of the 35 sprocket 52, thus stopping operation of the drills and of the drive shaft 36 which actuates the work support. The bearings 10 of the drill spindles 11 are slidably applied to the top frame member 9 which they over-lap at top and bottom, as at 10^a, being for that purpose supplied with a bored head through which pass tie-bolts 10^b secured at their rearward ends to back plates 10^c, whereby the bearings and spindles and thus 40 the entire drills A may be adjusted lengthwise of the machine and endwise of the frame member 9, and clamped in positions of adjustment by means of nuts 10^d threaded into the forward ends of the tie-bolts 10^b. 45 The frame member 9 preferably consists of an I-beam within the forward channel of which is disposed a relatively soft retaining plate 58 between which and the web of the beam 9 are disposed a metal back-plate 59. 50 and spacing blocks or strips 60, said plates and blocks being strapped to the beam web by tie-bolts 61 extending through said plates and the web and provided with nuts 62 rearward of the web, or by any other suitable means of attachment or adjustment. 55 The sprocket chains 13 and 16 ride in channels 13^a and 16^a formed in the forward face of the retaining plate 58, and are held thereby in one course of their movement to 60 the respective series of sprockets 12 upon

the drill spindles. The plate 58 by means of its attendant features may be blocked up and adjusted to effectively hold the link belts or sprocket chains to the sprockets to compensate for wear upon the retaining 70 plate.

The link 43 is preferably divided and provided with an elongated slot and pin connecting device whereby the bell crank 44 is thrown to throw out the clutches 31 and 32 when the arms 39 drop as permitted by the cams 37; this means of connection or play permitting the work support and work to be elevated into position for commencement of operation, through the agency of the hand 75 spokes 57, in the manner above described, without reversely throwing the bell crank 44 and seating the clutches 31 and 32, which latter operation is manually performed by the operator through the agency of the long 80 arm of the bell crank 44.

The operation and method of use of the gang drill mechanism constituting the invention has been set forth during the recitation of the construction and combination 90 and inter-relation of parts and features, and will be readily understood without further detailed description.

The staggered arrangement of the sprocket wheels 12 permits the same to over-lap so 95 that a closer assemblage of the drills is permitted, and a lesser spacing of the resultant drill holes is permitted, thus permitting a wider range of operation than otherwise possible.

It will be understood from the above description that each piece of work is plurally drilled as predetermined, and that upon the completion of the drill holes the work support drops with the work, the link 43 throwing out the clutches 31 and 32, terminating rotation of the operating shaft 36 and rotation of the drill spindles 11, no further drilling operation being performed until a fresh piece of work has been brought into position 105 and the clutches 31 and 32 are manually set as described.

Each drilling operation is thus independent of preceding and succeeding operations, and unskilled labor may thus be employed 110 in operating the machine without danger of injury to the person or work through uncontrolled operation.

Having thus described my invention, I claim and desire to secure by Letters Patent: 120

1. In a machine of the character disclosed, a drill, means for operating the same, a movable work support, means for operating the work support, and means operating automatically for jointly throwing out of operation the drill and the means for operating the work support.

2. In a machine of the character disclosed, a drill, means for operating the same, a movable work support, means for operating the 130

work support, and means operating automatically for jointly throwing out of operation the drill and the means for operating the work support; means being provided for independently operating the work support.

3. A gang drill machine, comprising a plurality of separate drills arranged in a working series, a drive shaft, and a single link belt operatively applied to all of the drills and to the drive shaft whereby the former may be operated upon rotation of the latter; each of said drills comprising a drill spindle provided with a drill proper and with a separate sprocket wheel which cooperates with said link belt.

4. In a machine of the character disclosed, a plurality of drills divided into two groups, and separate means for operating the drills of each group; said latter means including staggered sprockets the relative positions of which permit close assemblage of the drills.

5. In a machine of the character disclosed, a plurality of drills divided into two groups, a sprocket wheel mounted on each of said drills, said sprocket wheels being arranged in staggered relation, and separate link belts applied to the sprocket wheels of the respective drill groups for the operation of the drills.

6. In a machine of the character disclosed, a support, a drill spindle mounted upon the support, a sprocket wheel mounted on said drill spindle, a link belt applied to the sprocket wheel to operate the same, and means for holding the link belt in its travel to the sprocket wheel.

7. In a machine of the character disclosed, a support, a drill spindle mounted upon the support, a sprocket wheel mounted on said drill spindle, a link belt applied to the sprocket wheel to operate the same, and a recessed retaining plate connected with the support and holding the link belt in its travel to the sprocket wheel; means being provided for adjusting the retaining plate with respect to the support.

8. In a machine of the character disclosed, a support, a drill spindle adjustably mounted upon the support, a sprocket wheel mounted on said drill spindle, a link belt applied to the sprocket wheel to operate the same, and a recessed retaining plate connected with the support and holding the link belt in its travel to the sprocket wheel.

9. In a machine of the character disclosed, a frame provided with a transverse member and with upright members, a plurality of separate drills mounted upon the transverse member, a work support vertically movable upon the upright members, a shaft beneath the work support, a cam upon said shaft co-

operating with said work support, a vertical swinging arm connected with the work support and cooperating with said cam, means for operating said drills, means for operating said shaft, and means connected with said swinging arm for jointly throwing said drills and said shaft out of operation.

10. In a machine of the character disclosed, a plurality of separate drills each having a drive sprocket, said drills being divided into two groups, said sprockets being staggered, a drive shaft for each group of drills, operative connections between the drills of each group and its respective drive shaft, separate power applying shafts for the drive shafts, separate clutches for the power applying shafts, and means operatively connected with both clutches for rendering operative or inoperative the power applying shafts.

11. In a machine of the character disclosed, a plurality of separate drills, a separate drive sprocket on each drill, said drills being divided into two groups, said sprockets being staggered to permit close assemblage of the drills, a drive shaft for each group of drills, operative connections between the drills of each group and its respective drive shaft, separate power applying shafts for the drive shafts, separate clutches for the power applying shafts, and means operatively connected with both clutches for rendering operative or inoperative the power applying shafts; in combination with a movable work support, a drive shaft for the work support, means for operating the drive shaft jointly with the drills, cams upon the drive shaft for raising and lowering the work support, and means actuated by said cams for throwing the drive shaft of the work support out of operation automatically and jointly with the power applying shafts.

12. A gang drill machine, comprising a plurality of separate drills arranged in a working series, a drive shaft, and a single link belt operatively applied to all of the drills and to the drive shaft whereby the former may be operated upon rotation of the latter; each of said drills comprising a drill spindle provided with a drill proper and with a separate sprocket wheel which cooperates with said link belt; said drill spindles being relatively adjustable to permit variations in the grouping of the same.

In testimony whereof, I have signed my name to this specification in the presence of two subscribing witnesses.
